UNITED STATES PATENT OFFICE.

KELLY B. HARVEY, OF NEW YORK, N. Y.

AUTO TABLE AND CRANE.

Application filed October 31, 1922. Serial No. 598,101.

To all whom it may concern:

Be it known that I, KELLY B. HARVEY, a citizen of the United States, and a resident of New York city, in the county of New York and State of New York, have invented certain new and useful Improvements in Auto Tables and Cranes, of which the following is a specification.

This invention relates to mechanism for placing a motor vehicle on a stand above the ground or floor, and for the purpose of facilitating inspection and operations upon various parts of the vehicle.

The object of the present invention is to provide a device of this character by means of which an auto vehicle can be run or drawn up on the table or supported above the ground or floor, and which device is provided with means in the nature of a crane that will permit mechanism on the vehicle to be removed therefrom and swung to one side or beyond the vehicle.

A further object of the invention is to provide in such a device, means that will operate in the nature of a winch, to actuate the crane cable and which winch will also serve to draw the vehicle up on to the table.

In the accompanying drawing illustrating one embodiment of my invention Figure 1, is a perspective view.

Fig. 2, is a cross section on the line 2—2 of Fig. 1 at one end of the device.

Fig. 3 is a vertical section, partly in elevation at one end.

Fig. 4 shows a 60 degree Y.

Fig. 5 shows the thrust plate.

Fig. 6 shows the mast step plate.

Fig. 7 shows a detail on the top of the crane.

Fig. 8 is a plan of the latter.

The device as shown comprises essentially two members, an auto table and a crane. The former is shown as composed of a pair of side members 2 and 3 that are shown as channel shape. At one end these bars are connected by a cross bar 4, and supported by upright bars 5 and 6 that rest on a bottom bar 7, which bars are shown as of channel form. At the other ends the bars 2 and 3 are supported by four upright bars 8, 9, 10 and 11, which latter rest on a bottom bar 12. The two pairs of uprights on each side are connected by short bars 13 and 14. If desired the side bars may be supported by uprights 15 and 16 at the middle portion, that rest on angle bars 17 and 18.

I further provide inclined bars 19 and 20 at one end attached to the side bars 2 and 3, to run the vehicle up on to the side bars, either under its own power or by means of a 60 winch on the table.

In Figs. 1 and 3 I show a winch mounted on the cross bar 4 at the middle portion. This comprises essentially a bracket 21 supporting a drum 22 for the cable 23. A lever 65 24 swings at one side of the drum and carries a pawl 25 that engages the ratchet flange 26 of the drum. A stop pawl 27 on the frame also engages the ratchet 26. The cable 23 can be attached to the vehicle and 70 by swinging the lever, the car will be drawn up the inclined bars and on to the side bars 2 and 3.

A brake lever 24^A engages an asbestos lined brake band 24^B on drum 24^C for easing 75 cars down the inclined bars 19 and 20.

I further provide a crane at the front end of the auto table, that can swing over the car and also to one side or the end beyond the table. This crane I also arrange to be 80 operated by the cable 23 of the winch.

In the arrangement shown a pair of upright posts, such as angle bars 30 and 31 are secured to the end bars 4 and 7, on each side of the crane, and project upward a convenient distance.

These posts are connected at the top by a thrust plate 32, see Fig. 5, whose flanged ends 33, 33 are bolted between these posts, and the plate has a central opening 34, as a 60 guide for the mast 38, designed and constructed to receive all the lateral and downward thrusts under load. Below this thrust plate, is the mast step plate 35, with the flanged ends 36, 36 bolted to the angle bars 95 30 and 31. This plate has a mast socket 37 at the middle. The crane proper comprises a mast 38 preferably tubular, whose lower end is stepped in the socket 37, and which projects up through the opening 34 100 in the thrust plate 32 as shown. The crane also has a boom with supporting stays 44. The boom is shown in the form of a tube 39 that engages a holding member 40 on the mast shown in Fig. 4. This is the form of 105 a Y 41 having a flange 42 that rests on the thrust plate 32, at the circular opening 34 with the Y 41 loosely surrounding the mast 38. The other portion of the Y 43 is in the form of a step to receive the boom 39. The 110 latter extends upward and outward and at the top is secured to a pair of flat bar stays

44 and 45, whose opposite ends are secured to the top of the mast 38.

At the top of the mast 38 is mounted a sheave 46 between arms 47 and 48 on a bracket 49 extending into the mast, and a bolt 50 passes through the mast and this bracket, and the stays 44 and 45 are also secured by this bolt 50 to the mast. It will be observed that the grooved sheave 46 can receive and guide the cable 23 that passes upward through the tubular mast 38 directly from the drum 22 of the winch and then the cable 23 passes outwardly over the stays.

A sheave 51 is carried by the bracket 52 secured in the boom 39 by a bolt 53 passing through the boom 39 and the bracket which bolt also secures the stays 44 and 45 to the boom 39. It will be seen that the cable 23 passes over the sheave 51 and thence downwardly whereby its hooked end 54 can be connected with mechanism on the vehicle that has been run up on the side bars.

The brake lever 24^A engaging the asbestos lined brake band 24^B is also used to lower 25 away any load on the cable 23.

It will be understood that the crane can swing on the vertical axis of the mast in its supports in the cross plates, so that a part of the car can be raised by the cable and then 30 the cross arm swung outwardly to one side, or over the end of the table.

It will be further understood that the same cable or another cable wound on the drum 22 will permit the same winch that operates the crane, to be employed to draw 35 the vehicle up on to the auto table.

What I claim is:—

A crane composed of two upright angle bars, a cross plate at the top of the bars provided with a journal portion, a cross 40 plate connecting the angle bars below said plate and having a socket portion, an upright tubular mast mounted to turn in said socket and in said journal, a bracket having a collar surrounding said mast on top of 45 said upper cross plate, a tubular extension on said bracket inserted in the boom, a tubular boom engaging said bracket extension, a sheave bracket on the upper end of the boom inserted in the tubular boom, a sheave 50 bracket at the upper end of the mast, a pair of bars connecting the upper end of the mast with the outer sheave end of the boom, a cross bar connecting said angle bars and a winch on said cross bar arranged to operate its cable passing up through the said mast and over the said two sheaves on the 55 said mast and boom.

Signed at New York city, N. Y., on October 21, 1922.

KELLY B. HARVEY.
